UNITED STATES PATENT OFFICE.

WILLIAM R. FEARN, OF CAMDEN, NEW JERSEY, ASSIGNOR TO L. R. SCHWERIN, OF PHILADELPHIA, PENNSYLVANIA.

IRON POLISHER AND SUPPORT.

SPECIFICATION forming part of Letters Patent No. 580,263, dated April 6, 1897.

Application filed April 20, 1896. Serial No. 588,352. (No model.)

To all whom it may concern:

Be it known that I, WILLIAM R. FEARN, a citizen of the United States, residing at Camden, in the county of Camden and State of New Jersey, have invented certain new and useful Improvements in Iron Polishers and Supports, of which the following is a specification.

This invention relates to a new and useful improvement in sad-iron polishers and supports, and has for its object to provide a device of this description which will combine with a perfect support for the iron a polishing-surface by means of which the operating-surface of the iron may be kept in condition for proper operation upon the articles to be ironed.

With these ends in view my invention consists in the details of construction and combination of elements hereinafter set forth, and then specifically designated by the claims.

In order that those skilled in the art to which this invention appertains may understand how to make and use the same, I will describe its construction and operation in detail, referring by letter to the accompanying drawings, forming a part of this specification, and in which—

Figure 1 is a perspective of my improvement, showing it secured to an ironing-board or table and supporting a sad-iron; and Fig. 2, a cross-section of the device, illustrating the method of clamping the polishing-surface and distending the clamps.

Referring to the drawings, A represents a rectangular piece of asbestos cloth having the clamps B secured along its opposite sides, and these clamps are preferably formed of single strips of metal, so bent as to embrace the sides of the fabric, and provided with flanges C, bent at right angles to the body of the clamps.

D is the distender, composed of a single length of wire so bent as to provide arms E, adapted to pass between the parallel sections of the clamps outside of the edges of the fabric, as clearly shown in Fig. 2, and the center of this wire is formed into a hook F, adapted to engage the edge of a table or ironing-board, as clearly shown in Fig. 1. The wire from which the distender is made should be of suffi-

cient resiliency to maintain a constant outward draft upon the fabric, so as to hold the latter taut. When it is desired to fold the device into a small compass, it is only necessary to withdraw the distender from the clamps, when the fabric may be rolled or otherwise reduced within a small compass. The distender is shown partially withdrawn from the clamps in dotted lines in Fig. 1.

In practice the device is placed upon the table or ironing-board, within easy access of the operator, and the upper surface of the fabric coated with wax or other suitable polishing substance, and when it is desired to polish the face of the iron this is accomplished by moving it back and forth longitudinally over the surface of the fabric between the clamps, this position of the iron being shown in Fig. 2; and when it is necessary to support the iron, when not in use, it is placed crosswise of the device, so as to rest upon the flanges C, as illustrated in Fig. 1.

One of the principal advantages of this improvement is that the asbestos fabric has a slight abrading effect upon the face of the iron, and therefore removes all foreign substances and tends to burnish said face by the latter being moved back and forth thereon, and, as well known, a fabric composed of asbestos is an absorbent, and therefore will retain a large quantity of the polishing material when the latter has been applied in a liquid state, which is brought about, in the case of ordinary wax or paraffin, by the application of the hot iron to said material. Thus it will be seen that after the asbestos fabric becomes saturated with the polishing material the application of this material to the surface of the iron by the rubbing of the latter upon the fabric may be accomplished a number of times without the application of new polishing material to the fabric, as the heat of the iron will draw the polishing material to the surface of the fabric after the manner of a wick feeding oil.

Having thus fully described my invention, what I claim as new and useful is—

1. An iron polisher and support consisting of a section of asbestos cloth, clamps secured to the side edges thereof, flanges formed with said clamps for the support of the iron out of

contact with the polishing-surface, and a dis-
tender formed of a single piece of wire, the
parallel ends of which are adapted to engage
the clamps for holding the fabric taut and
5 having a hook for engagement with the edge
of a table or ironing-board, substantially as
and for the purposes set forth.

2. An iron polisher and support, consisting
of a sheet of asbestos cloth, strips of sheet
10 metal bent over opposite edges thereof each
having an edge bent up at a right angle to its
body portion and a spring-wire bent to form

a hook for engagement with a table edge or
the like and having parallel arms removably
slidable in the metal strips, as and for the 15
purpose described.

In testimony whereof I have hereunto af-
fixed my signature in the presence of two sub-
scribing witnesses.

WILLIAM R. FEARN.
